UNITED STATES PATENT OFFICE.

FRED I. GETTY, OF JENNINGS, LOUISIANA.

MACHINE FOR MANUFACTURING SCREENINGS FOR WELL-TUBES.

No. 892,659.

Specification of Letters Patent.

Patented July 7, 1908.

Application filed March 31, 1905. Serial No. 253,189.

To all whom it may concern:

Be it known that I, FRED I. GETTY, a citizen of the United States, residing at Jennings, in the parish of Calcasieu and State of Louisiana, have invented certain new and useful Improvements in Machines for Manufacturing Screenings for Well-Tubes, of which the following is a specification.

My invention relates to certain new and useful improvements in machines for manufacturing screening for well tubes, and its object is to produce a device of this class which shall have certain advantages which will appear more fully and at large in the course of this specification.

To this end, my invention consists in the novel features which are shown in the accompanying drawings as embodied in my preferred form of construction.

In the aforesaid drawings, Figure 1 is an elevation of my improved device, showing the same in use; Fig. 2 is a face view of the bracket which holds the wire-guide in an upright position; Fig. 3 is a section in the line 3—3 of Fig. 4, through the wire-guide; Fig. 4 is a section in the line 4—4 of Fig. 1, looking in the direction of the arrow; Fig. 5 is a top plan of the screen-forming mechanism; Fig. 6 is a front view of the same; Fig. 7 is a horizontal section in the line 7—7 of Fig. 4; Fig. 8 is a rear elevation of the mechanism; Fig. 9 is a section in the line 9—9 of Fig. 5; Fig. 10 is a perspective view of the supporting frame; Fig. 11 is a section in the line 11—11 of Fig. 1; looking in the direction of the arrow; Fig. 12 is an elevation of the forming rolls, looking from the left in Fig. 5; Fig. 13 is a horizontal section in the line 13—13 of Fig. 12; and Fig. 14 is a perspective view of the shifting shoe.

The type of screen which my improved device is designed to form is that wherein a wire having suitably-spaced lugs is wound around a perforated pipe. In practice, a long length of pipe is provided with perforations of the proper size and is wound with wire from end to end. The pipe thus prepared may be joined by suitable couplings, so as to produce any desired length.

Referring now to the drawings, A, indicates the pipe which is used, the same having a plurality of perforations, a, and being rotatably mounted in a lathe, B, of the ordinary form. While I prefer to use an ordinary machine lathe, it will be obvious that any device by which the pipe can be sym-

metrically and rotatably journaled will operate equally as well. In the use of my improved device, a frame, C, is mounted directly upon the pipe itself, the said frame being yieldingly pressed toward the left, as viewed in Fig. 1, by means of a weight, C¹, connected with the frame by a cord, c, running over pulleys, c². The frame C, has a rearwardly-projecting arm, C², which rests upon a rod, b, secured to the lathe-bed, said rod operating to limit the backward rotation of the frame as the pipe is rotated. In other words, the rod by engaging with the arm, C², prevents the frame from rotating, and causes it to remain stationary on the rotating pipe, although it permits it to slide longitudinally on the pipe against the pressure exerted by the weight, C¹.

The frame, C, it will be seen, is roughly U-shaped in form (see Fig. 10), and it is adapted to receive the pipe, A. At the forward end of the frame are three upwardly-projecting posts, c³, forming between them two notches, in which rest the forward ends of two straps, D, D¹, the said forward ends being held down by means of screws, d, passed through a plate, d¹, secured to the upper ends of the post, c³. Lock-nuts, d², are provided on the screws or bolts, d. The rear ends of the straps, D, D¹, are passed through holes, c², (Figs. 7, 8 and 10), in the upwardly-extending rear portion of the frame, C. The rear ends of these straps are likewise held down by means of set-screws or bolts, d³. The strap, D, has adjustably secured to it a guiding shoe, E, a bolt, e, serving to effect the connection, while the strap, D¹, carries a shifting shoe, E¹, connected therewith by a bolt, e¹. Both these shoes bear against the upper surface of the pipe and together they form the bearing which prevents downward movement of the frame with respect to the pipe. The shifting shoe, E¹, has other purposes which will presently be explained; but the shoe, E, serves only to furnish a large bearing conforming substantially to the surface of the pipe. It will be seen that the ends of the straps can be adjusted and the shoes can also be adjusted on the straps, so that any desired pressure can be obtained between the shoes and the pipe. When it is desired to operate on pipes of different diameters, the shoes can readily be removed and others substituted which will conform to its surface. In order to complete the centering of the frame, C, on the pipe, two other

bearings, at least, are obviously desirable. The first of these is provided by two rollers, F, (Figs. 4 and 7), mounted on a shaft, f, confined between shoulders, c³, on the rear side of the forward leg of the frame, C, and bearing-plates, c⁴, secured thereto. These rollers, F, as will be seen from Fig. 4, bear on the front side of the pipe above its center and tend to prevent backward, and, to a certain extent, downward movement of the frame on the pipe. The third bearing of the frame on the pipe is provided by two rollers, G, (Figs. 4 and 7) mounted on a shaft, g, carried on the ends of two triangular plates, G¹, pivoted at their upper ends to the opposite sides of the rear leg of the frame and provided with a lock-bolt, g¹, running in slots, g², by which they can be locked in any desired angular position. As a further means for fixing the position of the rollers, G, the plates, G¹, are provided on their lower edges with notches, g³, (Fig. 4) which are adapted to be engaged by the laterally-projecting ends g⁴, on a locking plate, G², (Fig. 25) adjustably secured to the rear face of the rear leg of the frame, C. It will be seen that the rollers, G, will coöperate with the rollers, F, and the shoes, E, E¹, to center a pipe, of any desired size, within the frame and will still leave the pipe free to rotate within the frame while the frame is free to slide longitudinally on the pipe. When a pipe of smaller diameter than the one shown in the drawings is used, the rollers, G, are swung up so that the pipe may be held at the proper height with respect to certain forming rolls hereafter described, in order that the wire may be properly fed to the pipe from said rolls.

40 The form of wire for which the machine herein illustrated is particularly designed, is that illustrated in my pending application for patent on strainers for wells filed December 1, 1904, and allotted Serial Number 45 235,124. This wire indicated in the drawings by, H, is T-shaped in cross-section, one of the edges, h, of the head of the T being plain, and the opposite edge, h¹, having a plurality of lugs, h². The head of the T, in practice, lies parallel to the axis of the pipe and the central web, h³, thereof lies at right angles to the pipe. It will be obvious that my device as far as many features are concerned could be used with wire of any desired cross-section; but since this is my preferred wire, I illustrate a machine for operating upon it. In the use of the machine, the wire is furnished in the form in which it is wound on the pipe, except that the opposite edges of the T-head are not fully formed until it reaches the machine. My machine, therefore, comprises the devices for guiding the wire, forming the flat surface and the lugged surface on the T-head, and winding the wire 60 upon the pipe. These devices will now be

described, beginning at the front of the machine where the first guiding device which the wire strikes is situated.

I, indicates a vertical roller which bears against one edge of the wire as it comes from the reel, holding the same between two vertical guide rollers, J, mounted upon a post, j. After the wire passes by the rollers, J, it passes between two rollers, K, L, the said rollers having horizontal grooves, k, l, respectively (see Fig. 12), the groove, l, being provided with a plurality of depressions, l¹. These two grooves, which are flat-bottomed, receive the T-head of the wire and bring it to the desired configuration. The wire in passing between these rolls, is crowded into the depressions or notches in the groove, l, thereby forming laterally-projecting lugs. When the screen is completed, the lugs on one turn of wire bear against the flat surface of the next turn, and consequently the height of the lugs determines the mesh of the screen. The height of the lugs is determined exactly by the depth of the notches, l¹, in the groove, l. In selling screening of this sort, it is necessary that its mesh shall correspond approximately to the meshes of ordinary wire gauze, and by using a set of interchangeable rollers, a single machine can be made to turn out wire suitable for forming screens with mesh corresponding to any of the standard gauze meshes. In order to make the change from one set of rollers to another a comparatively easy matter, I have adopted the bearing herein shown which is particularly simple and in which the rollers, K, L, can be changed with the greatest ease. It will be seen that said rollers, K, L, are mounted on shafts, K¹, L¹, being held in place between shoulders, K², L², and nuts, K³, L³. Bearing blocks, K⁴, L⁴, are provided for the shafts, K¹, L¹, respectively. These blocks are held in vertical guides formed between upwardly-projecting ribs or flanges, c⁵, on the frame, C, and a plate, C³, being laterally-adjustable by means of screws or bolts, k⁵, l⁵, (Fig. 5) and vertically-adjustable by means of screws or bolts, k⁴, l⁴, (Fig. 9). These blocks, it will be seen, are provided with slightly flaring adjacent faces, (Fig. 5) in which faces are semi-cylindrical vertical grooves adapted to receive the shafts, K¹, L¹. The blocks are provided with central, flat-bottomed notches, which afford space for the collars on the shaft, the grooved rollers and the lock-nuts for the same. The shoulders on the shafts rest against the flat bottoms of the notches in the bearing blocks and prevent longitudinal movement of the rollers with respect thereto. The device is assembled by placing the rollers in the proper relations to their respective bearing blocks and then placing the blocks in the guides. The parts are then firmly locked in position against any ordinary strain which could occur in practice. 120 125 130

The rollers can not be moved forward from the bearing blocks, because to move forward they must first swing together, and such movement is obviously impossible, because 5 the space between the bearing blocks is too small to permit it. Backward movement out of their bearings is likewise prevented in the same way, and yet when the ordinary strain of use, that is, a separating strain, is 10 placed upon the rollers, they have a perfect working bearing device. It will be seen, therefore, that whenever it is desired to change rollers for the purpose of making lugs of a different size, all that is necessary to do 15 is to remove the bearing blocks, exchange the roll, L, for another one and replace all the parts as before.

After passing from the rolls, K, L, the wire passes through a hole, v⁶, (Figs. 7 and 10) in 20 the front of the frame, C, and into a guide, M, composed of two plates, m, (see Fig. 3) held together by a screw, m¹. The space between these plates is channeled out to form a narrow slot which is grooved at its lower 25 end to receive the head of the T-shaped wire. The construction will be fully understood from Fig. 3, which shows the groove with the wire in place. This guide is supported by the wire itself, and is prevented from lateral 30 movement by means of a pin, m², running between flanges, n, on a guide, N, (Figs. 2 and 5). The guide, M, it will be seen, keeps the wire in its proper position, and fits it to the pipe with the T-head horizontal.

35 The only motive power which is used in operating my device is that applied directly to the pipe itself. One end of the wire is passed through the various guides and the forming rolls and secured to the pipe. The 0 pipe is then started in rotation and it draws the wire through the machine and winds it up, thus forming and winding it practically at one operation. The machine is shifted along the pipe by means of the shifting shoe, 5 E¹, heretofore referred to. This shoe it will be noted, has one edge, e², (Fig. 14) which is arranged to fit the plain edge of the wire, and this shoe always bears against the last turn of wire which was laid on the pipe, forcing 50 the same against the other turns to a certain extent; but being itself shifted along the pipe by reason of the spiral course of the wire.

I realize that considerable variation is possible in the details of this construction, with-

out departing from the spirit of my invention, and I do not intend to limit myself to the specific form herein shown and described.

I claim as new and desire to secure by Letters Patent:—

1. In a machine for making wire wrapped strainers, the combination with means for rotating a central core upon which the wire is to be wound, of a forming device adapted to operate on the wire as it passes to the core, said forming device being operated by the 60 pull of the wire imparted by the winding mechanism, and a shifting shoe connected to the forming device and arranged in such relation to the pass of the forming device as to engage the advance edge of the wire wrapped 65 on the core whereby the forming device is moved forward as the winding operation progresses.

2. In a machine for making wire wrapped strainers, the combination with means for rotating a central core upon which the wire is to be wound, of a pair of rolls through which the wire is drawn by the pull of the winding means in its passage to the core, and a shifting shoe connected to the rolls and arranged 75 in such relation to the pass between the rolls as to engage the advance edge of the wire wrapped 80 on the core, whereby the rolls are moved forward as the winding operation progresses.

3. In a machine for making wire wrapped strainers, the combination with means for rotating a central core upon which the wire is to be wound, of a lug-forming device comprising 90 a pair of rolls, one of which is provided with depressions into which the metal of the wire is compressed to form lugs, said lug-forming rolls being operated by the pull of the wire 95 imparted by the winding mechanism, and a shifting shoe connected to the forming device and arranged in such relation to the pass of the forming device as to engage the advance edge of the wire wrapped on the core, whereby the forming device is moved forward as the winding operation progresses.

In witness whereof I have signed the above application for Letters Patent at Jennings, in the parish of Calcasieu and State of Louisiana, this 21st day of March, A. D. 1905.

FRED I. GETTY.
